UNITED STATES PATENT OFFICE.

THOMAS C. HANSON, OF ROCKFORD, ILLINOIS.

SPIKE.

1,024,776.

Specification of Letters Patent.

Patented Apr. 30, 1912.

Application filed June 17, 1911. Serial No. 633,896.

To all whom it may concern:

Be it known that I, THOMAS C. HANSON, a citizen of the United States, residing at Rockford, in the county of Winnebago and 5 State of Illinois, have invented certain new and useful Improvements in Spikes, of which the following is a specification.

The object of this invention is to provide a key for locking a spike in position after 10 being driven in the tie.

In the accompanying drawings, Figure 1 is a vertical section of a spike with the key in place. Fig. 2 is an edge view of the key. Fig. 3 is a face view of the lower portion of 15 the key. Fig. 4 is a plan view of the spike and key. Fig. 5 is a section on line *a a* Fig. 1.

The spike is formed with the usual shank 1, point 2 and overhanging head 3. The 20 rear face of the shank is formed with a lengthwise extending groove 4, in this instance about two-thirds its length. A key is of rectangular form and comprises the main portion 5 provided with a head 6, an end portion 7, and an intermediate portion 8. The intermediate portion 8 is formed by the 25 V notch 9 between it and the main portion, and the V notch 10 between it and the end portion.

30 In use, the spike is driven into the tie 11 in the usual manner until its head 3 rests

in contact with the flange of the rail. The key is placed in the groove 4 of the spike so that the V notch 10 will face toward the inner wall of the spike and the V notch 35 9 will face outward. The end of the end section of the key will contact with the end of the groove 4 of the spike. By driving the key down, the material at the V notches will bend, thereby closing the notches which will 40 force the point of union between the intermediate section 8 of the key, and the end section 7 outward into the material of the tie as shown at Fig. 1 of the drawings. The key being thus bent will hold the spike from 45 withdrawing.

I claim as my invention.

A spike having a longitudinal groove, the end of which is substantially square, and 50 a key fitting the groove and provided with notches on opposite faces so that when driven into the groove will rest against the end of the groove and will be bent out laterally in V shape.

In testimony whereof I have hereunto set 55 my hand in presence of two subscribing witnesses.

THOMAS C. HANSON.
